UNITED STATES PATENT OFFICE.

GEORGE WM. GWYNN AND ANDREW GWYNN, OF SALT LAKE CITY, UTAH.

RAILWAY-SWITCH.

1,180,142.

Specification of Letters Patent. Patented Apr. 18, 1916.

Application filed November 5, 1914. Serial No. 870,335.

To all whom it may concern:

Be it known that we, GEORGE W. GWYNN and ANDREW GWYNN, citizens of the United States, residing at Salt Lake City, in the county of Salt Lake and State of Utah, have invented certain new and useful Improvements in Railway-Switches, of which the following is a specification.

Our invention relates to improvements in railway switches, and refers to that class of switches which are opened by means carried by the car.

The object of our invention is the provision of means which will be absolutely reliable in operation, which will be simple, strong and durable to withstand hard usage, and which will be inexpensive of production, to insure an efficient and practical improvement of this character.

With this object in view our invention consists of a railway switch embodying novel features and combination of parts substantially as shown, described and particularly defined by the claims.

Figure 1 is a plan view of the main track, switch or point and switch mechanism, Fig. 2 is a perspective view of the means for operating the switch mechanism and carried by the car, Figs. 3 and 4 are detail views of parts of the switch mechanism.

In the drawings:—The numeral 1 designates the main track; 2 the siding; and 3 the pivoted point which is confined in its movement by the strip or rail 4. In the surface between the rails is sunk the casing or box 5 and the larger casing or box 6, which are connected by the pipe 7, and coupling sleeves 8. In the casing 5 is formed a bracket 9, to which is pivoted at 10, the right angled shaped lever 11, one arm 10' of which has secured thereto the bracket plate 12, and in openings 13, of the arm and plate is mounted the pin 14, which projects up through the curved slot 15, in the cover plate 16. The pin is provided with a collar 14', against which and the arm 10', exerts the tension of a coiled spring this normally forcing the pin upward to project its upper end above the slot in the cover plate 16.

To the other arm 10' of the lever 11, is secured one end 17, of the rod 18 whose other end 19, is secured to the arm 20, of the angle lever 21, fulcrumed at 22, in the bracket 23, and having its other arm 24 formed near its end with an opening 25, to receive the threaded rod 26. Upon this

threaded rod is placed the pair of nuts 27, which serve to adjust the tension of the pair of coiled springs 28, which surround the rod 26, and bear at their outer ends against the nuts 27 and at their inner ends against the opposite faces of the arm 24. The arm thus has a spring or cushion connection with the threaded rod which prevents injury to the arm or rod and also permits the tension of the springs to be adjusted to suit the circumstances. The inner end of said threaded rod is mounted at 29, in the turn buckle 30, whose other threaded sleeve 29' receives the threaded end 31 of the pin 32, which is connected at its headed end 33, to the pivoted switch point. It will thus be seen that the two cases or boxes are arranged between the rails, sunk in the ground and protected from the elements by covers and that the pin 14, will always be retained above the cover of the case by the spring.

To operate the switch from the car we provide a novel mechanism which we will now describe.

The platform 34, of the car is provided with an opening 35, around which is secured the guide plates 36, the lower of which is formed with a sleeve 37, and guided in the opening and plates is the plunger 38, having at its upper end a treadle or foot pin 38' and having its lower end secured to the yoke shaped frame 39. To the frame 39 and the sleeve 37, are secured the pairs of plates 40, each having a hook 40', and to the hooks of the series of plates are connected the loops 41 on the pair of coiled springs 41'. It will thus be seen that the plunger is forced down by pressure of the foot and upon release of the foot the springs instantly raise the plunger with the yoke shaped frame 39 connected to the plunger.

To the frame at its lower ends 39' is secured the shoe for operating the switch mechanism and this shoe is of peculiar and novel construction and consists of the pair of oppositely flared arms 42, and the pair of oppositely flared guides or boxes 43, the pin 14, being first engaged by one of the arms 42 which moves the pin in the slot of the cover and which movement rocks the lever which carries the pin, which rocking of the lever pulls the connecting rod, and rocks the other lever and through this latter lever the pivoted switch is moved.

In operation the engagement of one member 42 with the pin 14 will partly throw the

switchpoint and the aligned member 43 continues the same motion of the switch point, the momentum of the switch point and the connecting mechanism carrying the pin 14 5 across the space between the members 42 and 43.

It will thus be understood that the shoe carried by the car is operated by pressure of the foot to switch the car from the main 10 to the side track and that the parts are always returned to normal position and that the services of an attendant are entirely dispensed with.

We claim:

- 15 1. In combination with a railway switch mechanism, of a pivoted switch point, connections for moving said switch point, a pin extending upward from said connections and a shoe having a pair of flared arms to engage said pin, a pair of communicating flared guides, a frame connected to said shoe, a plunger connected to the frame, a pair of plates having hooks and secured to the frame, a pair of stationary plates having 25 hooks, and springs secured to the hooks of the two pairs of plates for returning the plunger to normal position.
2. In a railway switch, the combination with the pivoted switch point, of a shoe for 30 operating said switch point, consisting of a pair of flared arms, a pair of communicating flared guides, a frame connected to said shoe, a plunger connected to said frame and pass-

ing up through the car floor, and means for returning the shoe to inoperative position. 35

3. In a railway switch, the combination with the pivoted switch point, of a shoe for operating said switch point, said shoe consisting of a pair of flared arms, a pair of communicating flared guides, a frame connected to said shoe, a plunger connected to said frame, a pair of plates secured to the car floor for guiding said plunger, and means for returning the shoe to inoperative position. 40

4. In a railway switch, the combination with the pivoted switch point, of a shoe for operating said switch point, said shoe consisting of a pair of flared arms, a pair of communicating flared guides, a frame connected to said shoe, a plunger connected to said frame, a pair of plates secured to the car floor for guiding said plunger, and means for returning the shoe to inoperative position, said means consisting of a pair of plates having hooks and secured to the frame, a pair of stationary plates having hooks and springs secured to the hooks of the two pairs of plates. 45

In testimony whereof we affix our signatures in the presence of two witnesses. 50
